UNITED STATES PATENT OFFICE.

WILLIAM H. THOMPSON, OF BERKELEY, CALIFORNIA.

PUMP.

Application filed June 17, 1924. Serial No. 720,481.

My invention relates to pumps, and particularly to gas circulating pumps of the double-acting reciprocating type.

An object of the invention is to provide a pump of the character described having inlet valves acting independently of the fluid pressure so that valve leakage may be reduced to a minimum.

Another object of the invention is to provide a pump of the character described which will maintain a substantially continuous flow of the fluid to be pumped at a predetermined pressure.

The invention possesses other objects and features of advantage, some of which, with the foregoing, will be set forth in the following description of the preferred form of my invention which is illustrated in the drawings accompanying and forming part of the specification. It is to be understood that I do not limit myself to the showing made by the said drawings and description, as I may adopt variations of the preferred form within the scope of my invention as set forth in the claims.

Referring to said drawings:

Figure 1 is a plan view, chiefly in section, of the fluid pump of my invention.

Figure 2 is a side sectional view taken on the line 2-2 in Figure 1.

Briefly expressed, the pump of my invention comprises a cylinder having an inlet port opening through its sides intermediate its ends, a hollow piston arranged for reciprocation over said port, and a passage in said piston communicating with said port. Openings from opposite ends of the piston cavity are valve controlled ports opening into the cylinder, the valves therefor being arranged to be operated by movement of the piston rather than by the fluid pressure relations as is the usual pump inlet valve. Outlet valves arranged to operate only at a predetermined pressure are arranged in opposite ends of the cylinder, so that the output of the pump may be delivered at a substantially invariable pressure.

As here shown, the pump of my invention comprises a casing 3 in which is provided a cylinder aperture 4 having end walls 5 and 6 and side walls 7. A piston 9 is arranged for reciprocation in the cylinder, the piston being preferably, as here shown, in the form of a cylindrical shell defining a cavity 11 therein and having valve seats 12 provided in the opposite ends thereof. Fluid is ar-

ranged to be introduced into the piston cavity 11 through an inlet port 14 which is preferably provided in the cylinder wall 7 intermediate the end walls. A longitudinally extending slot 16 is provided in the piston wall and registers with the port 14 to allow the introduction of fluid to the piston cavity during the reciprocation of the piston. It will thus be noted that by forming the piston slot 16 slightly longer than the stroke of the piston that the port 14 and slot 16 will be constantly in registration, thus allowing the passage of fluid therethrough independently of the position of the piston in the cylinder.

To control the flow of fluid from the piston cavity into the cylinder, valves 17, arranged to fit the seats 12, are provided. As here shown, the valves 17 fixedly mounted on a valve stem 18 extending longitudinally through the piston and slidably carried in bearings 19 provided in the end walls 5 and 6 of the cylinder, the valves 17 being in opposed relation and spaced so that when one valve is seated in one seat 12, the other will be held out of its seat. In this manner, it will be noted that at the beginning of a stroke of the piston, the forward seat 12 will contact with a valve 17 to close the forward end of the piston cavity, after which the valves and piston will be moved forward together during the balance of the stroke. Since movement of the piston is thus arranged to close the forward valve, a quicker closing will result than if a valve is provided which must be operated by the pressure against the head of the cylinder, thus reducing the possible back flow of fluid to a minimum. With the rearmost valve thus unseated, an unimpaired flow of fluid is allowed from the piston cavity into the portion of the cylinder being vacated by the piston. Complete evacuation of fluid from the forward portion of the cylinder is provided for by arranging the valves to abut the end walls of the cylinder at the ends of the strokes of the piston.

Discharge of fluid from the cylinder ends is preferably provided for by means of adjustable spring ball-valves 20 provided at opposite ends of the cylinder to allow the escape of fluid through passages 21 associated therewith, these passages terminating in nozzle openings 22. It will now be noted that with fluid supplied continuously to the piston cavity at a substantially constant

pressure, the compression and discharge of fluid occurs in the portion of the cylinder adjacent one end of the piston while the portion of the cylinder being vacated receives a new charge. The foregoing operation, in combination with the action of the adjustable valves 20, provides a practically continuous discharge of fluid, so that the pump of my invention is particularly useful for circulating a gas at a constant pressure as is particularly required in refrigerating plants and the like.

To provide for the ready longitudinal movement of the ends of the valve stem 18 in the bearings 19, I preferably provide longitudinal passages 23 extending from the ends thereof and opening through the side of the stem adjacent the valves. To prevent escape of fluid around the piston, piston rings 25 are preferably provided at opposite ends of the piston.

Actuation of the piston may be effected in any desired manner. As here shown, a transverse slot 26 is provided centrally of the piston in which a block 27 is arranged to be reciprocated by means of a wrist pin 28 carried on a disc 29 mounted on a shaft 31 for rotation in the frame and revolvably engaged in the block 27. Revolution of the disc is thus arranged to produce a reciprocative movement of the piston, the speed of such movement being least at the ends of the strokes thereof, thus avoiding any "hammering" of the piston. It will be noted that the engagement of the block in its seat prevents rotation of the piston.

This disc is arranged to be rotated in any desired manner. As here shown, rotation of the disc is effected by means of a worm gear 32 mounted on the shaft 31 and arranged to be driven by means of a worm gear mounted on a motor driven shaft 33.

It will now be noted that a pump has been provided which is positive, smooth, and efficient in action and which is arranged to occupy a minimum of space.

I claim:

1. A fluid pump comprising a cylinder

having closed ends, bearings provided in said ends, an inlet port arranged in a side thereof intermediate said ends, and outlet ports arranged adjacent said ends; a piston having a cavity therein arranged to communicate with said inlet port and having outlets arranged in opposite ends thereof; a valve stem slidably mounted in said bearings; and oppositely disposed valves fixed on said stem and arranged to alternately engage said piston cavity outlets, said valves and stem being arranged to be reciprocated with said piston.

2. A fluid pump comprising a cylinder having closed ends, an inlet port arranged in a side thereof intermediate said ends, and outlet valves arranged adjacent said ends; a piston having a cavity therein arranged to communicate with said inlet port and having outlet openings arranged in opposite ends thereof; means for reciprocating said piston; a valve stem extending through said piston cavity outlet openings and slidably mounted in said cylinder ends; and valves fixed on said valve stem in opposed relation and arranged to be reciprocated with said piston, the forward valve being seated in the forward piston opening, and the rearward valve being unseated during a given stroke of the piston.

3. In a double acting fluid pump a cylinder having an inlet port intermediate its ends and outlet ports adjacent its ends, a hollow reciprocable piston arranged to have the cavity thereof in constant communication with said inlet port and having valve openings arranged in the ends thereof, bearing sockets provided at the ends of said cylinder, a valve stem mounted for reciprocation in and between said sockets, and oppositely disposed valves mounted in fixed relation on said stem and arranged to alternately engage said piston valve openings upon reciprocation of said piston.

In testimony whereof, I have hereunto set my hand at Oakland, California, this 2d day of June, 1924.

WILLIAM H. THOMPSON.
